UNITED STATES PATENT OFFICE.

AARON WARFIELD, OF TORONTO, ONTARIO, CANADA.

CEMENT RAILWAY-TIE AND RAIL-FASTENING.

No. 926,788.

Specification of Letters Patent.

Patented July 6, 1909.

Application filed January 22, 1908. Serial No. 412,210.

To all whom it may concern:

Be it known that I, AARON WARFIELD, of the city of Toronto, in the county of York and Province of Ontario, Dominion of Canada, a citizen of the United States of America, have invented a new and useful Cement Railway-Tie and Rail-Fastening, of which the following is a specification.

My invention relates to a railway tie, cast or formed from cement, and having formed therewith, metal fastening plates, adapted to receive means for adjustably attaching the rails to the tie. The combination of the fastening plates besides forming a base for the rails, also acts as a strengthening means for the tie, especially cross-wise. Besides the fastening plates, I cast in the tie a series of rods, in parallel and longitudinal positions, to thoroughly reinforce the tie lengthwise. The object of casting or forming the tie from cement, is to provide for uniformity in size and weight, also to lengthen the life of the tie, as the cement is impervious to dampness, and will not be subject to decay therefrom. Heat will also have no effect on the cement to cause dry rot.

The fastening means provided in combination with the fastening plates, are adapted to attach and allow the rails to be detached as often as required, in a manner that they will in no way affect or destroy the tie. The fastening means are also of such a nature, that rails may be set at different gages, also for rails of different widths, especially those formed with wider and narrower bases, without in any way altering the tie or fastening plates. The fastening means are so constructed that adjustments may be quickly and minutely made, and very rigidly hold the rail to the tie, and provide against misplacement. The fastening means may also be adapted to any railway tie, as well as for the purpose herein described and illustrated. I attain these objects by my invention as illustrated in the accompanying drawings, in which—

Figure 1 is a perspective view of a section of track; Fig. 2 is a perspective view of one of the ties; Fig. 3 is a cross sectional view on lines *a—a* Fig. 2; Fig. 4 is a longitudinal sectional view on lines *b—b* Fig. 2; Fig. 5 is an end view of one of the ties with a section of rail and fastening means; Fig. 6 is a detail view of a section of the end of a tie showing a section of a rail and fastening means; Fig. 7 is a perspective view of one of the fastening

plates, Fig. 8 is a side elevation of one of the fastening dogs; Fig. 9 is a perspective view of one of the locking keys; Fig. 10 is a perspective view of one of the fastening dogs; Fig. 11 is a perspective view of an alternative form of locking key; Fig. 12 is a perspective view of a section of a tie and rail with an alternative form of fastening means; Fig. 13 is a longitudinal sectional view on lines *c—c* Fig. 12.

Like characters refer to like parts throughout the drawings and specifications.

a designates the tie, formed from cement, the regulation length and width, preferably rectangular in cross section. Cast in the tie longitudinally and parallel, are a series of bars *b*, for the purpose of reinforcing the tie lengthwise, also cast in the tie are fastening plates *c—c*, one at each end flush with the top face. The fastening plates *c* are formed with a top and two sides *c'—c'*, the sides ending with an out turned right angle flange *c²*, whereby they form an anchor to set in the cement to prevent misplacement or withdrawal. The fastening plates *c—c* also act as a strengthening means, to strengthen the tie crosswise.

d designates the fastening dogs by which the rails may be fastened to the tie, and *e* designates the locking key by which the dogs are adjustably fastened to the fastening plate *c*.

Formed through the top face of the fastening plates *c* are a series of openings, arranged in duplicates, the openings 1—1 being for the purpose of receiving the lugs *d'* of the fastening dogs *d*, and the openings 2—2 being for the purpose of receiving the wedge shaped heads *e'* of the locking keys *e*.

The fastening dogs *d* are formed with a socket *d²* adapted to receive the circular end *e²* of the locking key *e*. Formed through the sides of the dog *e* are a series of openings *d³* through which may be passed a cotter-pin or plug, to aid in holding the locking key in rigid engagement with the fastening dog.

Formed in the tie *a*, preferably when being cast, are a series of pockets *a'*. The pockets are situated immediately beneath the openings 1 and 2 in the fastening plates *c* and are for the purpose of admitting the flanges and heads of the fastening dogs and locking keys respectively, when being adjusted and fastened to the fastening plates.

f designates a tie-bar, for the purpose of coupling the two fastening plates *c* together

and maintain them against lateral displacement. The ends of the tie are riveted to the adjacent edges of the fastening plates, and are embedded in the cement with the fastening plates.

In fastening the rail *g* to the tie, a fastening dog *d* is arranged on each side of the rail, with the head *d*⁴ engaging over the base flange *g*' of the rail. The dog *d* engages and is fastened in the fastening plate *c*, by inserting the lug *d*' into the cross-slot 3 forming part of the opening 1, and is then forced forward into the opening 1 where it is prevented from being forced upward by projections *d*⁵, one 15 extending laterally from each side of the lug *d*', and adapted to engage under the edges of the fastening plate.

To prevent displacement of the dogs *d* and to lock them in position, I provide the locking key *e*, formed with a circular end *e*² adapted to engage in the socket *d*² in the dog *d*. The opposite end of the locking key is formed with a wedge shaped head *e*', having a series of notches *e*³ formed along its 25 outer edge.

To lock the dog *d* in its adjusted position in the fastening plate, the end *e*² of the locking key is inserted into the socket *d*² in the dog, and the wedge shaped head *e*' is inserted 30 into the slot 2 in the fastening plate and is forced or pounded downward until one of the notches *e*³ springs under the edge of the fastening plate *c*, by which it will be firmly held and may not be removed unless by the aid of 35 a lever or wedge which may be inserted under the center part of the locking key to force it up and spring it out of engagement with the edge of the fastening plate. The edge of the slot against which the notches engage is 40 chamfered so that it may more readily engage in the notches. It will be understood that where a rail with a very narrow base flange is being fastened, the wedge shaped head will be forced farther downward, and in 45 the opposite case where a very wide base flange is in use the wedge shaped head will not enter into the opening as far. By this means of fastening it will be seen, a very perfect adjustment is provided for without in 50 any way affecting the tie, or the fastening plate formed therewith.

Slight modifications may be made to the fastening plates by eliminating the sides and anchor flanges to adapt them to be fixed to 55 wooden ties, whereby the rails may be fastened to the tie as herein described. The fastening dogs and locking keys as herein described, are also adapted to be used in combination with metal railway ties for fastening 60 the rails to the same.

The slots 1 in which the lugs of the locking dogs engage are sufficiently long to permit of the lateral adjustments on each side of the rail.

95 In Figs. 11; 12 and 13, I have shown an

alternative form of fastening for the rail. The tie 10 in this form is identical with the former, also fastening plates 11 are cast therein. In the alternative form, I eliminate the locking dog, and instead thereof I substitute a locking key 12 that fulfils the dual purposes, and the locking plate is only provided with one set of openings 13, in which engages the locking key. The locking key 12 is formed with a clamping jaw 14 at one 75 end, adapted to engage over the base flange *m* of the rail *n*, and under the edge of the fastening plate. The opposite end of the locking key 12 is formed with a wedge shaped head 15, and formed along its outer 80 edge are a series of notches 16, adapted to engage with the chamfered edge 17 of the fastening plate. To fasten the rail to the tie, the locking key is inserted into the opening 13 in the fastening plate, and is forced 85 forward until the jaws 14 engage over the flanges *m* of the rail *n*, and under the edge of the fastening plate 11, the head 15 of the locking key is then driven down into the slot 13, until one of the notches 16 engages 90 with the chamfered edge 17 of the fastening plate, by which it will be held firmly against lateral movement or from rising.

In Fig. 8 I have shown a slightly modified form of the locking dog. Formed integral 95 with the head *d*⁴, is a raised fin *o*, adapted to engage against the web of the rail, to act as a further means for engaging with the rail.

With a railway tie as herein described, I provide means by which a very flat and uniform 100 railway bed may be constructed, and also a tie provided with fastening means by which the rail may be very quickly adjusted, and whereby the frequency of adjustment will have little or no effect as regards destruction.

Slight modifications may be made in the shape and construction of the fastening dogs and locking keys, without deviating from 110 the nature of my invention.

The essential features of my invention lie in the construction of a railway tie from cement, the means of reinforcing it lengthwise and crosswise, as well as the means for fastening to a cement body without fear of 115 chipping or working loose by vibration.

What I claim as new and desire to secure by Letters Patent, is—

1. In a cement railway tie and means for fastening rails to the same, a tie formed from 120 cement, a series of bars cast in parallel and longitudinal position in said tie, metal fastening plates cast with said tie, tie bars coupling said fastening plates together, a series of openings formed through the top of said fastening plates, pockets formed in the said tie beneath said openings, a series of fastening dogs adapted to be fastened in the openings in the said fastening plates, locking keys 125 adapted to engage with the said fastening 130

dogs, said locking keys also adapted to adjustably engage in openings formed in the said fastening plates, said locking keys adapted to adjustably fasten said fastening 5 dogs to said fastening plates, said fastening dogs and locking keys adapted to adjustably fasten the rails to said tie, substantially as described.

2. In a cement railway tie and means for fastening rails to the same, a tie formed from cement, a series of bars cast in parallel and longitudinal position in said tie, metal fastening plates cast with said tie, side walls and anchoring flanges formed with said fastening plates, tie bars coupling said fastening plates together, openings formed through the top of said fastening plates, pockets formed in the tie beneath said openings, a series of fastening dogs adapted to be adjustably fastened in said fastening plates, lugs formed on the bottoms of said fastening dogs, said lugs adapted to adjustably engage in the said openings, sockets formed in the said fastening dogs, locking keys adapted to engage in the said sockets and adjustably engage in openings formed in the said fastening plates, said locking keys adapted to adjustably fasten the said fastening dogs to the said fastening plate, said fastening dogs and 30 locking keys adapted to adjustably fasten the rails to the said tie, substantially as described.

3. In a cement railway tie and means for fastening rails to the same, a tie formed from cement, a series of bars cast in parallel and longitudinal position in said tie, metal fastening plates cast with said tie, tie-bars coupling said fastening plates together, a series of openings formed through the top of said fastening plates, pockets formed in said tie beneath said openings, fastening dogs adapted to be adjustably fastened in the said fastening plates, lugs formed on the bottom of the said fastening dogs, said lugs adapted to adjustably engage in the openings formed in the said fastening plates, sockets formed in the said fastening dogs, locking keys adapted to engage in the said sockets and also engage in the openings formed in said fastening 50 plates, said locking keys adapted to fasten the said fastening dogs to the said fastening plates, said fastening dogs and locking keys adapted to adjustably fasten the rails to the tie, substantially as described.

55 4. In a cement railway tie and means for fastening rails to the same, a tie formed from cement, a series of bars cast in parallel and longitudinal position in said tie, metal fastening plates cast with said tie, side walls

and anchor flanges formed with said fastening plates, tie bars coupling said fastening plates together, a series of openings formed through the top of said fastening plates, pockets formed in the tie beneath said openings, a series of fastening dogs adapted to be adjustably fastened in said fastening plates, fastening lugs formed on the bottom of said fastening dogs, said lugs adapted to adjustably engage in the said openings in said fastening plates, sockets formed in the 70 said fastening dogs, locking keys adapted to engage with the said dogs and fastening plates, one end of said locking key adapted to engage in the socket formed in the said fastening dog and the opposite end adapted to adjustably engage in one of the openings formed in the said fastening plates, said locking key adapted to adjustably fasten said fastening dog to the said fastening plate, said fastening dog and fastening key adapted 80 to adjustably fasten said rail to the said tie, substantially as described.

5. In a railway tie and means for fastening rails to the same, a tie having fastening plates fixed thereto, a series of openings 85 formed through the top of said fastening plates, a series of fastening dogs adapted to adjustably engage in the openings formed through the said fastening plates, a series of locking keys adapted to engage with the said 90 locking dogs and in openings formed through the said fastening plates, said locking keys adapted to adjustably fasten the said fastening dogs to the said fastening plates, said fastening dogs and locking keys adapted to 95 adjustably fasten the rails to the said tie, substantially as described.

6. In a railway tie, a fastening means comprising fastening plates adapted to be fixed to said tie, a series of openings formed 100 through the said fastening plates, a series of fastening dogs having lugs formed thereon, said lugs adapted to adjustably engage in the openings in the said fastening plates, a series of locking keys adapted to engage with the 105 said fastening dogs and adjustably engage in openings formed through the said fastening plates, said fastening dogs and locking keys adapted to adjustably fasten the rails to the said tie, substantially as described.

Signed at Toronto, this 30th day of November, 1907.

AARON WARFIELD.

In the presence of—

J. N. BLACK,
A. A. ADAMS.
